UNITED STATES PATENT OFFICE.

VARANUS A. WOLCOTT, OF SCHENECTADY, NEW YORK, ASSIGNOR TO GENERAL ELECTRIC COMPANY, A CORPORATION OF NEW YORK.

ACCELERATION-CONTROLLING DEVICE.

No. 928,013.

Specification of Letters Patent. Patented July 13, 1909.

Application filed May 16, 1908. Serial No. 433,211.

To all whom it may concern:

Be it known that I, VARANUS A. WOLCOTT, a citizen of the United States, residing at Schenectady, county of Schenectady, State 5 of New York, have invented certain new and useful Improvements in Acceleration-Controlling Devices, of which the following is a specification.

Under certain conditions it is desirable 10 that a prime mover accelerate rapidly on decrease in load. Since decrease of load will, of course, when energy is supplied at the normal rate, cause a certain positive acceleration of the prime mover, it is evident that the latter will accelerate more rapidly if the energy furnished it during acceleration is supplied at a rate above normal.

My invention has for its object to provide 20 means responsive to positive acceleration of a prime mover for increasing above normal the rate at which energy is supplied thereto during acceleration. It may, as will be obvious to those skilled in the art, be carried out in connection with a steam engine, gas engine, electric motor, or any other form of prime mover and, although in this application I have shown and described it in connection with an electric motor, I do not wish to be understood as limiting it to this form of 25 translating device.

It is customary to provide mining locomotives with a cable reel which winds up and pays out a flexible conductor attached to a source of current and serving to supply current to the locomotive when it is "gathering" cars from the working faces of mines. Such an arrangement is shown in the patent 35 to Shaver, No. 853,522, dated May 14, 1907, cable reel apparatus for mining locomotives, 40 in which the reel is shown as driven by a small motor. It has been found necessary under certain conditions that the reel motor be accelerated very rapidly during acceleration of the locomotive toward the source of 45 current supply, in order to positively insure the slack in the cable being reeled up and the tension thereon being maintained substantially constant. It is in connection with this line of apparatus that my invention is particularly useful, and for the purposes of 50 illustration I have shown it embodied in a device of this kind. I do not wish to be understood, however, as limiting my invention to use with this particular kind of apparatus since, 55 as will be obvious to those skilled in this art,

it may equally well be used in many other connections; for example, for the control of electric motors employed, in connection with devices for coaling ships at sea, for keeping taut the cable extending from one vessel to another.

The mining locomotive of the kind above described, chosen for the purposes of illustration, is provided with the form of cable reel made the subject of a co-pending application in the name of Carl W. Larsen, Serial No. 414,459, filed February 6, 1908. The particular arrangement which I have illustrated comprises means including an inertia operated device, rotated by the reel motor, 65 which, during acceleration of the reel motor owing to acceleration of the locomotive toward the source of current supply, will increase above normal the voltage applied to the reel motor, by, for example, short-circuiting a resistance normally interposed in the motor circuit.

The invention will be fully understood from the following description taken in connection with the accompanying drawings, in 70 which—

Figure 1 is a side elevation of an electric mining locomotive having a cable reel applied thereto, in connection with which my invention is shown in the other figures; Fig. 2 75 is a cross-sectional elevation through the reel, most of the driving mechanism thereof being shown in elevation; Fig. 3 is a top view of the reel showing the inertia operated device hereinafter described; and Fig. 4 is a dia- 80 grammatic view showing the arrangement of 85 circuits and the parts which control them.

Referring to the drawings, in which like parts are indicated throughout the several views by the same reference characters, in 90 Fig. 1 the frame of the electric locomotive is shown in outline with the wheels 5 mounted in any suitable manner in journal boxes upon which the frame of the locomotive rests. Mounted on the top of the locomotive is the 100 reel 6 upon which is wound a flexible conductor 7 which runs through a sheave 8 and has its end secured in any suitable manner to a source of current, such as a trolley wire 9.

The construction of the reel proper and the 105 arrangement of the driving mechanism may be of any suitable kind and is shown the same, except for differences hereinafter mentioned, as that set forth in the Larsen application above referred to. The reel proper 110

may be built up from a wooden disk 12 to which are secured a plurality of bent metal ribs 13 which may be connected at their outer ends by a ring 14 in order to give them stability, while extending from the top of the disk 12 may be ribs 15 connected at their outer ends by a ring 16. The driving mechanism of the reel is supported by a frame 20, of the form shown, which frame is mounted upon the locomotive and serves not only for the support of the reel, but also as the field frame of the main motor which drives the reel. The field coils of this motor are shown at 21, and in co-operative relation to these rotates an armature suitably journaled in the frame 20. On the lower extended end of the armature shaft is a gear 22 which engages with a gear 23 keyed to a countershaft journaled in a cylindrical extension 24 of the frame 20. Keyed to the upper end of this countershaft is a pinion 25 which engages with a gear 26 arranged for rotation on the top of the frame 20. The disk 12 of the reel rests upon the upper extended surface of this gear 26 and the frictional engagement between these two parts drives the cable reel, a disk 27 of fibrous or other suitable material being interposed to insure proper wearing of the parts.

The construction so far described is substantially the same as that illustrated in the Larson application, above referred to, but, if desired, the reel may have a positive driving connection with the motor equivalent to that shown in the patent to Shaver, No. 853,322, above mentioned.

Secured to the bottom of the disk 12 are two rings 30 and 31 of conducting material with which engage, respectively, brushes 32 and 33 mounted in any suitable manner in an extension 34 of the frame 20. A terminal 35 connects with the brush 32, while a terminal 36 connects with the brush 33. The end of the flexible conductor 7 is secured to a terminal 37 electrically connected with the ring 30, as clearly shown in Fig. 2. Mounted upon the top of the reel is an inertia operated device best shown in Figs. 2 and 3 as comprising a bar 40 pivoted freely at 41 at the axis of the reel, which bar has at each end a heavy enlarged head 42. This bar 40 is connected to and caused to rotate with the reel by a spring 43 secured to the bar at a suitable point and connected to a fixed pin 44 on the top of the reel. The bar 40 carries at 45 a contact which when the bar is rotated on its pivot against the tension of the spring 43 bridges two fixed contacts 46 and 47. The contact 46 is electrically connected to the ring 31, and the contact 47 is electrically connected to the ring 30, as shown in Figs. 2 and 4.

The inertia of the rod 40 and the tension of the spring 43 are such that upon acceleration of the reel in a direction to wind up the ca-

ble, the rod 40 in its movement will lag behind the reel sufficiently to elongate the spring 43 and bring the contact member 45 into engagement with the fixed contacts 46 and 47. A stop 48 projecting upwardly from the top of the reel may be provided to prevent the bar 40 from moving in an opposite direction with reference to the reel when the reel is rotated to unwind the cable.

The reel motor, which is preferably series wound, is connected on one side to the frame of the locomotive, in other words to ground, and on the other side through a resistance R to the terminal 35 of the brush 32. The terminal 36 leading to the brush 33 is connected to a point between the resistance and the reel motor. These connections are best shown diagrammatically in Fig. 4 and, as will be understood from that figure, result in connecting the reel motor to the supply cable 7 in series with the resistance R under normal conditions, this resistance being short-circuited when the contact 45 controlled by the inertia operated device bridges the fixed contacts 46 and 47. The inertia operated device might of course equally well be elsewhere arranged and driven more directly from the reel motor or, in fact if desired, might be driven from an axle of the locomotive.

The operation of the embodiment of my invention, above described, will be understood from Fig. 4. While the locomotive is at rest or operating at a constant speed or moving away from the source of current, the reel motor will be connected to the source through the resistance R and will exert a certain torque upon the reel tending to wind up the cable. When, however, the locomotive is accelerated toward the point at which the cable 7 is secured, thereby allowing the reel to accelerate and wind up the cable, the inertia operated device will bring the contact 45 into engagement with the contacts 46 and 47 and will temporarily connect the rings 30 and 31, thereby short-circuiting the resistance R, the effect of which will be to apply a higher voltage to the motor thereby increasing the torque thereof and causing the motor to accelerate more rapidly than it otherwise would. As soon as the locomotive comes to a constant speed, or is decelerated, the inertia operating device opens the contacts controlled by it and reinserts the resistance in the motor circuit, thereby reducing the torque of the motor to its normal value.

While I have shown but one form in which my invention may be embodied, I do not wish to be understood as limiting it thereto, except as called for by the following claims.

What I claim as new and desire to secure by Letters Patent of the United States, is,—

1. In combination, a vehicle, a cable reel carried thereby, a source of current, a reel motor connected thereto supported on said

vehicle and arranged to rotate said reel, and means for automatically increasing the voltage applied to said motor during acceleration of said vehicle in one direction.

2. In combination, a vehicle, a cable reel carried thereby, a source of current, a reel motor connected thereto supported on said vehicle and arranged to rotate said reel, and means including an inertia operated device 10 for increasing above normal the voltage applied to said reel motor during acceleration of said vehicle in one direction.

3. In combination, a vehicle, a cable reel carried thereby, a source of current, a reel 15 motor connected thereto supported on said vehicle and arranged to rotate said reel, and means including an inertia operated device carried and operated by said reel for increasing above normal the voltage applied to said 20 reel motor during acceleration of said vehicle in one direction.

4. In combination, a vehicle, a cable reel carried thereby, a source of current, a reel motor connected thereto supported on said 25 vehicle and arranged to rotate said reel, and means for automatically increasing the voltage applied to said reel motor during acceleration thereof.

5. In combination, a vehicle, a cable reel 30 carried thereby, a source of current, a reel

motor connected thereto supported on said vehicle and arranged to rotate said reel, and means including an inertia operated device for increasing above normal the voltage applied to said reel motor during acceleration 35 thereof.

6. In combination, a vehicle, a cable reel carried thereby, a source of current, a reel motor connected thereto supported on said vehicle and arranged to rotate said reel, a resistance normally in series with said motor, and means for automatically short-circuiting said resistance during acceleration of said vehicle in one direction. 40

7. In combination, a vehicle, a cable reel carried thereby, a source of current, a reel motor connected thereto supported on said vehicle and arranged to drive said reel, a resistance normally in series with said motor, and means including an inertia operated device mounted upon said reel arranged to short-circuit said resistance during acceleration of said vehicle in one direction. 45

In witness whereof, I have hereunto set my hand this 15th day of May, 1908.

VARANUS A. WOLCOTT.
